UNITED STATES PATENT OFFICE.

WILLIAM MITTERREITER, OF PARIS, TENNESSEE.

SHOE-SHINING DEVICE.

1,168,409.

Specification of Letters Patent. Patented Jan. 18, 1916.

Application filed July 28, 1915. Serial No. 42,402.

To all whom it may concern:

Be it known that I, WILLIAM MITTERREITER, a citizen of the United States, residing at Paris, in the county of Henry and 5 State of Tennessee, have invented a new and useful Shoe-Shining Device, of which the following is a specification.

This invention relates to an improvement in shoe shining devices, and the object is to 10 provide means for shining the entire shoe at one operation, that is, the polishing cloth will travel over the toe and around the heel of the shoe, so that practically the entire shoe is polished.

15 A feature of this invention is the simplicity of construction, and that it can be manufactured and sold at a small cost.

The invention consists of certain novel features of construction and combinations 20 of parts which will be hereinafter described and pointed out in the claims.

It is evident that various changes in the form, proportion, size and minor details of construction, within the scope of the appended claims, may be resorted to without departing from the spirit and scope, or sacrificing any of the advantages of the invention.

In the accompanying drawings:—Figure 30 1 is a view in side elevation of the invention; Fig. 2 is a top plan view; Fig. 3 is a transverse sectional view on the line 3—3 of Fig. 1; and Fig. 4 is a view in front elevation, showing the manner of mounting the 35 front posts.

A, represents the base, and 1 is a web connected thereto, upon which is supported a foot plate 2. The base A and vertical web 1 may be cast in a single piece, or made 40 from wood or other material. The foot plate is removably connected to the web 1 by means of screws 3 or other fastenings.

Extending transversely of the foot plate 2, and over the toe portion thereof, is a toe 45 cloth or polisher 4. Each end of the toe cloth 4 is connected to the terminal of a strap 5. The straps 5 pass beneath rollers 6 journaled on shafts or pins 7, which shafts or pins are journaled in longitudinal recesses or grooves 8 formed in the sides of the base A. Eyes or loops 9 connect the shafts or pins 7 to the base A, the eyes or loops being mounted on shoulders 10 at the ends of the recesses or grooves 8 for holding

the shafts 7 and rollers 6 at a sufficient elevation to permit the straps 5 to pass freely between the base and shafts. 55

Connected to the outer terminals of the straps 5 are fabric or cloth hand loops 11, so that the straps may be actuated for causing the toe cloth to be moved transversely across the shoe supported on the foot plate 2. Pads 12 are formed between the loops 11 and the straps 5 to provide a polisher for the shoe at the arch portion. 60

65 A heel cloth or polisher 13, of preferably U-shape construction, is intended to pass around the heel of a shoe and along the sides thereof. Connected to the ends of the heel cloth 13 are straps 14. The straps 70 14 pass through the looped ends 15 of posts 16, and around rollers 17 rotatably mounted on the posts. The outer terminals of the straps 14 are connected to the main or toe straps 5 near their outer terminals, and upon the operation of the toe straps 5, the straps 14 will be actuated to cause the heel cloth or polisher 13 to be moved about the surface of the shoe for polishing the same. 75

The posts 16 are located at the forward end of the foot plate 2, and on each side thereof. A transverse plate 18 is connected to the toe portion or forward end of the foot plate 2, and is provided with openings 19 at the ends thereof through which the 80 posts 16 extend. Sockets or holes 20 are formed in the base A, at the forward end thereof in which the lower terminals of the posts are received for maintaining the posts in position. The upper ends of the posts 16 85 are bent forwardly at an acute angle, and then downwardly and inwardly forming closed loops 15. This formation maintains the rollers 17 at an acute angle, so that the straps 14 which pass therearound are prevented from traveling upwardly and causing the heel cloth 13 to be drawn onto the 90 stocking or above the top of the shoe. 95

To prevent the posts 16 from rotating or becoming displaced, a rod 21 is removably mounted in a transverse slot 22 formed between the upper surface of the web 1 and the lower surface of the foot plate 2, at the forward ends of the web and foot plate. The rod 21 is provided with hooks 23 which 100 are adapted to pass through the loops 15 and engage the posts for holding them stationary. 105

A heel plate 24 is countersunk in the heel portion of the foot plate 2, and is provided with a longitudinal slot 25, through which screws 26 pass for fastening the heel plate 5 to the foot plate. The screws 26 limit the outward longitudinal movement of the heel plate, and normally the heel plate rests in retracted position, or wholly within the countersunk portion of the foot plate. A handle or tongue 27 limits the inward movement of the heel plate. The heel plate is intended to be drawn outwardly by the handle or tongue 27 after the heel cloth or polisher 13 has been applied to the shoe to 10 be polished, to prevent the cloth from slipping off from the shoe and coming into engagement with the rear terminal of the web 1.

Connected to the base A at each side of 20 the web 1 are coil springs 28, which are connected to cords 29, of leather or other suitable material. The cords 29 are connected to the inner corners of the toe cloth or polisher 4, and to the straps 5. The springs 25 prevent the cloths or polishers 4 and 13, from slipping beyond the toe of the shoe and hold them against the sides of the shoe.

From the foregoing it will be seen, that when the straps 5 are operated, that is, by 30 first pulling upwardly on one strap, and then on the other, that the toe and heel cloths or polishers will be caused to move about the shoe for polishing the same. When desired, the heel cloth need not be 35 applied, but can be left in engagement with the rear end of the web 1, and the toe cloth used. The toe cloth may be used independently of the heel cloth whenever the operator so wishes, as the straps can be manipulated for operating the toe cloth in the same manner as though the heel cloth was applied to the shoe.

When both the heel and toe cloths are in 45 position for polishing the shoe, the rollers 17 and springs 28 will maintain the heel cloth in position, and the springs 28 will prevent the toe cloth from sliding too far over the toe of the shoe.

The rollers 6 and 17 will relieve the friction 50 on the straps, to a great degree, in the operation of the polishers, and will cause the straps to be drawn at the proper angle for causing the polishers to operate properly upon the shoe.

The base, web and foot plate, form a support 55 for a shoe, and when the straps 5 are operated, by first pulling upwardly on one strap and then upwardly on the other, the toe cloth or polisher is moved transversely 60 of the shoe, and the heel cloth or polisher is drawn around the heel of the shoe and along the sides, for polishing the toe, heel and sides of the shoe simultaneously. Upon the completion of this operation, the pads 65 12 can be rubbed along the arch of the shoe

for polishing that surface of the shoe which will not be entirely polished by the heel cloth.

What is claimed is:—

1. A shoe shining device comprising a toe cloth, a heel cloth, guides for the cloths to hold the same in their respective positions against the shoe, and a single operating means connected to the adjacent ends of the toe and heel cloths to simultaneously draw 70 the same back and forth over the respective parts of the shoe.

2. A shoe shining device comprising a toe cloth, a heel cloth, guides for the cloths to hold the same in their respective positions 80 against a shoe, and a hand strap secured to each pair of opposite adjacent ends of the toe and heel cloths for actuating the same simultaneously upon the reciprocating movement of the hand straps.

3. A shoe shining device, comprising a shoe support, a toe cloth adapted to extend transversely of the toe portion of a shoe, a heel cloth adapted to extend around the heel and along the sides of a shoe, guides at 85 the forward end of the shoe to receive the ends of the heel cloth thereover, straps connected to the terminals of the toe cloth for causing the toe cloth to be moved transversely of the shoe, and means for connecting 90 the said ends of the heel cloth to the straps, whereby said heel cloth is adapted to be moved longitudinally of the shoe and the toe cloth transversely of the shoe.

4. A shoe shining device, comprising a 100 shoe support, a toe cloth adapted to extend transversely of the toe support, straps connected to the ends of the toe cloth, a heel cloth having straps connected thereto, posts connected to the forward end of the shoe 105 support having rollers thereon, said heel straps extending around the rollers and connected to the toe straps, and rollers connected to the shoe support, beneath which the toe straps extend, whereby upon the operation of the straps for moving the toe cloth 110 transversely, the heel straps will be actuated for causing the movement of the heel cloth.

5. A shoe shining device, comprising a 115 shoe support, a toe cloth adapted to extend transversely of the toe and instep portion of a shoe, a heel cloth adapted to extend around the heel and along the sides of the shoe, straps connected to the toe cloth, rollers connected to the shoe support and located 120 below the toe cloth, beneath which the toe straps extend, posts connected to the forward end of the shoe support having rollers thereon, straps connected to the heel cloth and extending around the rollers and connected 125 to the toe straps, whereby the toe cloth and heel cloth will be simultaneously reciprocated upon the actuation of the toe straps, and springs connected to the shoe support, and loosely connected to the toe straps and 130

heel cloth, for maintaining the heel and toe cloths in proper position on the shoe during the shining operation.

6. A shoe shining device, comprising a shoe support, a toe cloth adapted to extend across the toe portion and instep of a shoe, and a heel cloth adapted to extend around the heel and along the sides of the shoe, posts connected to the forward end of the shoe support having the upper ends thereof bent outwardly, rollers connected to the outwardly extending ends of the posts, toe straps connected to the toe cloth, straps connected to the ends of the heel cloth, and passing around the rollers on the posts and connected to the toe straps, whereby the toe and heel cloths will be simultaneously operated upon the actuation of the toe straps, said outwardly extending ends of the posts being adapted to maintain the heel cloth in position on the shoe.

7. A shoe shining device, comprising a shoe support, a heel cloth adapted to extend around the heel and sides of a shoe, posts removably connected to the forward end of the shoe support having the upper ends thereof bent outwardly and downwardly forming loops, rollers mounted on the outwardly extending portions of the posts, straps connected to the ends of the heel cloth and passing around the rollers and through the loops of the posts for maintaining the heel cloth in position on the shoe, a rod having hooks on the ends thereof en-

gaging the loop portions of the posts for holding the posts against movement, said shoe support being provided with a slot at the forward end thereof in which the rod is received, and means connected to the heel straps for causing the operation of the heel cloth upon the actuation of said means.

8. A shoe shining device, comprising a shoe support, a heel cloth adapted to extend around the heel and sides of a shoe, a heel plate slidably mounted on the shoe support at the rear end thereof, said heel plate being adapted to be drawn outwardly from the rear end of the shoe support to prevent the heel cloth from sliding off from the heel of the shoe, and means connected to the heel cloth for operating the same.

9. A shoe shining device, comprising a shoe support, a toe cloth adapted to extend transversely of the toe portion of the shoe, a heel cloth adapted to extend longitudinally of the shoe, resilient means connected to the toe and heel cloths for maintaining them in the proper operative position relatively to each other and to the shoe, and means connecting the toe and heel cloths, whereby they are adapted to be operated simultaneously.

In testimony, that I claim the foregoing as my own, I have hereto affixed my signature in the presence of two witnesses.

WILLIAM MITTERREITER.
